(57) **CLAIM**

The ornamental design for a lid for beverage container as shown and described.

DESCRIPTION

FIG. 1 is a top perspective view of a lid for travel beverage container showing our new design;

FIG. 2 is a bottom perspective view of the lid for travel beverage container of FIG. 1;

FIG. 3 is a front side view of the lid for travel beverage container of FIG. 1;

FIG. 4 is a back side view of the lid for travel beverage container of FIG. 1;

FIG. 5 is a left side view of the lid for travel beverage container of FIG. 1;

FIG. 6 is a right side view of the lid for travel beverage container of FIG. 1;

FIG. 7 is a top side view of the lid for travel beverage container of FIG. 1; and,

FIG. 8 is a bottom side view of the lid for travel beverage container of FIG. 1.

Features of the lid for travel beverage container shown in dashed line or bounded by broken line form no part of the claimed design.

1 Claim, 8 Drawing Sheets
